(57) **CLAIM**

The ornamental design for a blade fuse and fuse element therefore, as shown and described.

DESCRIPTION

FIG. 1 is a perspective view of a blade fuse and fuse element therefore showing my new design;

FIG. 2 is a front view thereof;

FIG. 3 is a side view thereof;

FIG. 4 is a top view thereof;

FIG. 5 is a bottom view thereof; and,

FIG. 6 is another perspective view of a blade fuse and fuse element therefore showing the fuse element in relation to a phantom, claimed, outer casing of the blade fuse for clarity.

The broken line portion of the figure drawings is included to show unclaimed subject matter only and forms no part of the claimed design.

The special dot-dash broken line in FIG. 6 of a phantom, claimed, outer casing of the blade fuse is employed for the sake of clarity in order to show the complete fuse element within.
